Patented Oct. 3, 1899.

W. D. CONKLIN.

CALCULATOR.

(No Model.)

(Application filed Nov. 2, 1898.)

FIG. 1.

FIG. 2.

FIG. 3.

FIG. 4.

UNITED STATES PATENT OFFICE.

WILLIAM D. CONKLIN, OF RUTHERFORD, NEW JERSEY, ASSIGNOR OF ONE-HALF TO JAMES J. MCKENZIE, OF SAME PLACE.

CALCULATOR.

SPECIFICATION forming part of Letters Patent No. 633,989, dated October 3, 1899.

Application filed November 2, 1898. Serial No. 695,289. (No model.)

To all whom it may concern:

Be it known that I, WILLIAM D. CONKLIN, of Rutherford, in the county of Bergen and State of New Jersey, have invented a new and Improved Calculator, of which the following is a full, clear, and exact description.

This invention relates to a calculator designed especially for calculating wages, the wage per hour, day, or week, and number of hours of service being given.

The invention is also applicable to other matters of calculation, as will appear from the following description.

This specification is the disclosure of one form of my invention, while the claims define the actual scope thereof.

Reference is to be had to the accompanying drawings, forming a part of this specification, in which similar characters of reference indicate corresponding parts in all the figures.

Figure 1 is a plan view of the invention with parts broken away. Fig. 2 is a sectional view on the line 2 2 of Fig. 1. Fig. 3 is a similar view on the line 3 3 of Fig. 1. Fig. 4 is a plan view of one of the sliding cover-plates, and Fig. 5 is a perspective view of one of the sliding amount-plates.

The drawings show a calculator adapted to calculate wages up to ten dollars per week and twenty hours of service. It will of course be understood that this is a mere fragment of the complete apparatus, which will in practice be very much enlarged to meet the requirements of practical operation. Ordinarily it will be desirable to enlarge the calculator so that it will permit calculating wages as high as twenty-five or thirty dollars per week and for as many as seventy or eighty hours' service in each week. Ordinarily persons are employed at so much per week, counting sixty hours as one week. It is rare, of course, that employees make exactly sixty hours each week. Some weeks less time and other weeks more time will be served. This device is adapted, essentially, therefore, to the calculation of the proper pay to be given for the number of hours served each week.

The apparatus is placed in a tray or box 6, constructed, preferably, of wood and in convenient form to be laid upon a desk or counting-table. Situated in the tray or base 6 is a

bed-plate 7, on which are laid a number of parallel strips 8, spaced apart from each other, so that the sliding amount-plates 9 may be laid between them, with the edges of the plates 9 against the adjacent edges of the plates 8. The plates 8 and 9 are of the same thickness, and the plates 9 have finger-pieces 10 attached thereto, by which to slide the plates 9, the outward-sliding movement of the plates being limited by the walls of the base or tray 6. The plates 9 are provided with a series of numbers 11, which represent the amount of pay due to the employee for the certain number of hours which he has served.

Laid across the plates 8 and 9 and transversely thereof are spacing-plates 12, similar to the plates 8 and having cover-plates 14 arranged between them edge to edge. These plates 14 slide as do the plates 9, except that they move in lines at right angles to the plates 9. The cover-plates 14 are manipulated by finger-pieces 15 and are provided with openings 16, which openings are one for each of the amount-plates 9, the purpose of said openings being to upon the outward movement of the plates 14 expose the numbers on the plates 9, as is shown in reference to one of the cover-plates in Fig. 1, such cover-plate being moved outward to expose the number 94 on one of the amount-plates 9.

Laid on the upper faces of the plates 12 and 14 is a face-plate 17, which is formed with a series of regularly-arranged openings 18, through which may be read the indications of the calculator. All of the parts 7, 9, 14, and 17 are held rigidly together by means of bolts or other desired fastening devices 19 passed through said parts and situated so as not to interfere with the sliding plates 9 and 14. This construction provides, therefore, a rigid framework in which the two tiers of sliding plates 9 and 14 are arranged, the tier 14 being above the tier 9 and the two sets of plates sliding at right angles, the plates 9 to bring the numbers 11 in position for exposure and the plates 14 to move the openings 16 over the numbers, and thus effect the desired exposure of the number that is moved into position by the movement of the plate 9. The calculator being placed in the box or

tray 6 is held snugly thereby, and the walls of the box serve to limit the outward movement of both sets of plates 9 and 14.

Each of the cover-plates 14 is indexed by a number, such as the number "20," such number representing the amounts per week that are paid to the employees, and each plate 9 is indexed by numbers, such as the number "21," these numbers indicating the hours that are served by the employees. Assuming, therefore, that an employee is paid three dollars and seventy-five cents per week of sixty hours and that this employee serves fifteen hours as a certain week, his wage is calculated therefor by drawing out the cover-plate 14 that is indexed by the number "20," as "\$3.75," and the amount-plate 9, that is indexed by the number "21," as "15," is also drawn out. This moves up for exposure the number "94" on the said amount-plate 9, and the adjacent opening 16 in the cover-plate will expose this number, which represents the amount due the employee—that is to say, ninety-four cents. I will not explain the system by which the plates 9 are provided with the numbers "11," since this is a mere matter of mathematical calculation that is well understood.

Various changes in the form, proportion, and minor details of my invention may be resorted to without departing from the spirit and scope of my invention. Hence I do not consider myself limited to the precise details herein shown, but I am entitled to all such variations as come within the scope of my claims.

Having thus described my invention, I

claim as new and desire to secure by Letters Patent—

1. A calculator of the character described, 40 comprising a base-plate provided with sets of guideways arranged one above the other and at right angles to each other, imperforate plates sliding in the lower set of the guideways and each bearing numbers representing 45 the amounts of pay due for a certain number of hours, and indexed to indicate the hours served, perforated plates sliding in the upper set of guideways and each indexed to indicate the amount of wages for a given time, 50 and a perforated face-plate above the said sliding plates, substantially as described:

2. A calculator of the character described, 55 consisting of a tray or box, a base-plate in the tray or box and of less area than the same, 55 said base being provided with sets of guideways arranged one above the other and at right angles to each other, imperforate plates sliding in the lower set of guideways and each bearing numbers representing the amounts 60 of pay due for a certain number of hours, perforated plates sliding in the upper set of guideways, and a perforated face-plate secured to the base-plate above the guideways, said face-plate being provided on one edge 65 opposite the perforated plates with numbers representing the wages for a given time and on another edge opposite the amount-plates with numbers representing the hours served, substantially as described.

WILLIAM D. CONKLIN.
